UNITED STATES PATENT OFFICE.

JOHN A. HELLSTROM, OF WHEELING, WEST VIRGINIA.

SHEET-OPENING MECHANISM.

Application filed February 1, 1922. Serial No. 533,442.

To all whom it may concern:

Be it known that I, JOHN A. HELLSTROM, a subject of the King of Sweden, and resident of Wheeling, county of Ohio, and State of 5 West Virginia, have invented certain new and useful Improvements in Sheet-Opening Mechanisms, of which the following is a specification.

This invention relates to machines for separating metal sheets, and more particularly 10 to a mechanism for effecting the separation of sheets which have become bonded in the rolling of a sheet-metal pack.

The primary object of the invention is 15 to provide a simple and efficient device whereby metal sheets bonded together in rolling may be mechanically separated or stripped each from the other in an expeditious manner involving the separate gripping of such sheets and the positive advance 20 thereof on opposite sides of a stationary splitting element.

A further object is to provide a mechanism of the character mentioned which has a 25 construction providing for practically instantaneous release of the sheets, as when withdrawal of the latter is desired.

In describing the invention in detail, reference is herein had to the accompanying 30 drawings, in which—

Figure 1 is a longitudinal section of a machine embodying my invention, and—

Figure 2 is a section on line 2—2, Fig. 1.

Referring to said drawings, 1 indicates 35 roll housings in which are arranged suitable bearings 2 and 3 carrying positively driven rolls 4 and 5 having their axes located in a common vertical plane. Said rolls are located a considerable distance apart, and in- 40 terposed therebetween are two relatively smaller rolls 6 and 7 which have their axes located in the aforesaid vertical plane, said smaller rolls having their opposite ends journaled intermediate the ends of substan- 45 tially horizontal carrier bars 8 of suitable length which are disposed in slots or recesses provided in the opposite housings 1, having their rear ends pivotally mounted upon pivot pins or bolts 9 mounted in said hous- 50 ings.

Rigidly carried by said carrier bars 8 rear- 55 ward of the intermediate rolls 6 and 7 are the opposite ends of a transverse spreader bar 10 which is herein shown to be of semi-cylindrical form in cross section with its flat face presented toward said intermediate

rolls, though it may have any other suitable form. Carried by the forward end portions 8^a of said bars 8 is a horizontal transversely disposed plate 11 upon opposite sides of 60 which the separated sheets emerge and are directed to a suitably located delivery table, as 12.

The driven roll 4 is vertically movable, the bearings 2 therefor being carried by vertical rods 13 which are normally maintained by supporting springs 14 in elevated positions. Said roll is adapted to be thrust downward against the tension of said 70 springs by means of adjustable pressure screws 15 carried by the housings, as ordinarily.

The forward end portions 8^a of the bars 8 rest upon coil springs 16 which normally hold said bars in an upwardly-swung position in which the lower of the intermediate rolls is elevated out of cooperative sheet-advancing relation to the lower of the driven rolls. Adjustable stops are also employed for limiting the upward swing of said 80 bars 8. Said stops, as herein shown, comprise arms 17 pivoted intermediate their ends upon pins 18 mounted in the housings and having depending nose-like inner ends 17^a overhanging the forward end portions 8^a 85 of said bars. Screws 19 carried by the outer ends of said arms 17 have their lower ends resting upon supporting lugs 20 formed on the housings and are adapted for adjustment to position the arms 17 for arresting 90 the elevating movement of the bars 8 at any desired height.

In practice, the operator spreads apart the edges of one end of a pair of adhering sheets, commonly termed "stickers," and 95 with said sheets supported, or partially supported, upon a suitably located feed table 21, directs said edges of the sheets on opposite sides of the spreader bar to points wherein the upper thereof is introduced between the 100 upper driven roll 4 and the upper intermediate roll 6 and wherein the lower thereof is introduced between the lower driven roll 5 and the lower intermediate roll 7. The roll adjusting screws 15 are then lowered 105 for thrusting said upper driven roll 4 into cooperative sheet-gripping relation to the roll 6 and for depressing the intermediate rolls 6 and 7 to a point in which the roll 7 assumes cooperative gripping relation to the 110 lower driven roll 5, said lowering movement being effected, first, against the tension of

the springs 14, and, second, against the tension of springs 16. Tractive force exerted by the rolls acts to separately advance said sheets, drawing the latter at a uniform speed 5 over opposite sides of the spreader bar 10, whereby said sheets are forcibly stripped each from the other.

Should it at any time become desirable or necessary to stop the advance movement of 10 the sheets, the same may be promptly effected by such a partial rearward rotation of the roll adjusting screws 15 as may be necessary to permit withdrawal of the upper driven roll 4 from frictional gripping relation to the underlying sheet. Such movement of said screws 15 may be effected by any suitable known means or instrumentality. Obviously, due to the fact that intermediate, or friction, rolls 6 and 7, actuated 15 by the springs 16, follow the upward movement of the upper driven roll 4 until the portions 8^a of the carrier bars 8 strike against the stop-arms 17, the lower of the sheets is released contemporaneously with 20 the release of the upper sheet.

What is claimed is—

1. A sheet-opening mechanism comprising a pair of driven rolls, a pair of rolls located intermediate said driven rolls with their axes 30 in the same plane with those of said driven rolls, said intermediate rolls being adapted to be driven by friction from said driven rolls, yieldable means normally supporting said intermediate rolls in a position where- 35 in the lower thereof is out of operative relation to the lower driven roll, means for shifting the upper driven roll to and from a position in which it depresses said intermediate rolls against the tension of said 40 yieldable means, and a spreader element located in front of said intermediate rolls.

2. A sheet-opening mechanism comprising a pair of driven rolls, a pair of rolls located intermediate said driven rolls with 45 their axes in the same plane with those of said driven rolls, said intermediate rolls being adapted to be driven by friction from said driven rolls, yieldable means normally supporting said intermediate rolls elevated 50 in an inoperative position with respect to the lower driven roll, means for shifting the upper driven roll into and out of operative relation to the upper intermediate roll, said upper driven roll being adapted to depress 55 said intermediate rolls against the tension of said yieldable means, and a transversely disposed sheet-spreading member located in front of said rolls.

3. A sheet-opening mechanism comprising 60 separated driven rolls, a pair of friction

rolls of relatively small diameters interposed between said driven rolls, all of said rolls having their axes in a common plane, means normally supporting said friction rolls in a position in which the lower thereof 65 is out of pressure-exerting relation to the lower driven roll, the upper driven roll being movable into and out of depressing relation to the friction rolls and adapted in its lowered position to cause each of said friction rolls to assume sheet-advancing relation to the adjacent driven roll.

4. A sheet-opening mechanism comprising a pair of driven rolls, a pair of rolls located intermediate said driven rolls with 75 their axes in the same plane with those of said driven rolls, said intermediate rolls being adapted to be driven by friction from said driven rolls, substantially horizontal carrier bars in which said intermediate rolls 80 are mounted, said bars being pivotally mounted on the housings, yieldable means normally supporting said bars in a position in which the lower of said intermediate rolls is withdrawn from operative relation 85 to the lower driven roll, means for shifting the upper driven roll to and from a position in which it depresses said intermediate rolls against the tension of said supporting means, and a sheet-spreading member located in front of said rolls.

5. A sheet-opening mechanism comprising a pair of driven rolls, a pair of rolls located intermediate said driven rolls with 90 their axes in the same plane with those of said driven rolls, said intermediate rolls being adapted to be driven by friction from said driven rolls, substantially horizontal carrier bars in which said intermediate rolls are mounted, said bars being pivotally mounted on the housings, yieldable means 95 normally supporting said bars in positions in which the lower of said intermediate rolls is withdrawn from operative relation to the lower driven roll, means for limiting the 100 extent of elevating movement of said bars, means for shifting the upper roll to and from a position in which the lower of said intermediate rolls is caused to assume co- 105 operative relation to the lower driven roll against the tension of said supporting means, and a stationary element on opposite sides of which sheets advanced by said rolls 110 are drawn.

In testimony whereof, I affix my signature 115 in presence of two subscribing witnesses.

JOHN A. HELLSTROM.
